BOTTLE

John Brady Campbell, Paramus, N.J., assignor to The Procter & Gamble Company, Cincinnati, Ohio, a corporation of Ohio

Filed May 15, 1964, Ser. No. 79,989

Term of patent 14 years

(Cl. D58—6)

FIG. 1 is a front elevational view of a bottle showing my new design.

FIG. 2 is a side elevational view thereof.

FIG. 3 is a top plan view thereof.

FIG. 4 is a cross-sectional view taken on the line 4—4 of FIG. 1.

FIG. 5 is a cross-sectional view taken on the line 5—5 of FIG. 1.

FIG. 6 is a cross-sectional view taken on the line 6—6 of FIG. 1.

FIG. 7 is a bottom plan view.

The side and rear not shown are substantially the same as the side and front shown.

I claim:

The ornamental design for a bottle, as shown and described.
